Patented Jan. 10, 1922.

UNITED STATES PATENT OFFICE.

ERNEST VICTOR STONE, OF TAFT, CALIFORNIA.

APPARATUS FOR TREATING MINERAL OILS.

1,403,457.

Specification of Letters Patent. Patented Jan. 10, 1922.

Application filed May 27, 1920. Serial No. 384,716.

To all whom it may concern:

Be it known that I, ERNEST VICTOR STONE, a citizen of the United States, residing at Taft, in the county of Kern and State of California, have invented new and useful Improvements in Apparatus for Treating Mineral Oils, of which the following is a specification.

This invention is an apparatus for treating mineral oils and has for its object the provision of an apparatus including a cracking chamber having means for heating one end thereof for vaporizing the mineral oils, and also having means for cooling the opposite end thereof for condensing the vaporized oils.

It is a further object of the invention to provide an apparatus of this character including means for positively removing the carbon deposits which accumulate within the cracking chamber.

It is a still further object of the invention to provide means for introducing a flushing oil into the cracking chamber for dissolving and flushing out the tarry compositions formed within the cracking chamber when the vaporous mineral oils are condensed.

It is a still further object of the invention to provide a circulating system for the flushing oil including means for cooling a portion of the mineral oil distillates withdrawn from the cracking chamber and then returning said cooled mineral oil distillates to the cracking chamber for producing the flushing action in the cracking chamber.

The invention will be readily understood from the following description of the accompanying drawings, in which—

Figure 1 is a longitudinal section through an apparatus constructed in accordance with the invention.

Fig. 2 is a transverse section on the line 2—2 of Fig. 1.

Fig. 3 is a detail longitudinal section on the line 3—3 of Fig. 1.

In the practical embodiment of the invention, as illustrated, I have shown a furnace 1 which may be of any preferred construction, the heating means for the furnace being shown at 2. The cracking chamber is shown at 3 as a closed cylindrical shell extending through and beyond the furnace 1. The cracking chamber is adapted to be revolved upon its longitudinal axis for which purpose it is shown as provided with rings 4 fixed upon its outer surface, preferably, adjacent

its respective ends, these rings resting upon rollers 5 which are journaled upon shafts 6 supported in suitable brackets 7. These brackets rest upon a suitable foundation so as to form supporting means for the cracking chamber which will include means for causing revolution of the cracking chamber.

The mechanism for turning the cracking chamber may include a ring gear 8 upon the outer surface of the cracking chamber, said ring gear meshing with a pinion 9 which may be fixed upon one of the shafts 6. Any suitable means may be provided for rotating the shaft and thus turning the cracking chamber through the driving connection 8 and 9, said means for rotating shaft 6 being shown as including a pulley 10 fixed upon said shaft.

An attrition tube 11 extends through the cracking chamber and is rotatable therein either in the same direction, or in opposite direction to the direction of revolution of the cracking chamber. This attrition tube is arranged to make contact with the wall of the cracking chamber throughout only a portion of the circumferences of the attrition tube and the cracking chamber, the points of contact changing throughout the turning of the attrition tube and the cracking chamber. For this purpose the attrition tube is formed as an oblique cone having one side 11^a extending parallel with and resting against the wall of the cracking chamber and its remaining portion 11^b inclined relative to the wall of the cracking chamber.

The base 11^c of the conical attrition tube, preferably, fits snugly within the cracking chamber, and the ends of the attrition tube are, preferably, spaced somewhat from the ends of the cracking chamber, the attrition tube being shown as a frustum of a cone. By this arrangement it will be seen that when the cracking chamber is revolved and the attrition tube is rotated therein, the tube and chamber will always make contact throughout a portion of their circumferences and this contact portion will constantly change throughout the circumferences of the chamber and tube by which arrangement carbon deposits, accumulating upon the walls of the tube and chamber, will be removed as soon as formed by the contact between the tube and chamber.

The means for rotating the attrition tube in either direction within the cracking chamber may include a shaft 12 extending

through a suitable stuffing box 13 and through one end of the cracking chamber to a point adjacent the base of the conical attrition tube at which point it is connected by a universal joint 14 to a stub shaft 15 projecting axially from the base of the attrition tube. The shaft 12 may be journaled in a suitable bearing bracket 16 supported upon the foundation of the apparatus, and the driving connection for this shaft may include a gear 17 fixed upon the shaft and meshing with a pinion 18 upon a suitable countershaft 19 which may be driven in any suitable manner including a pulley 20 upon the counter-shaft. The mineral oils to be cracked are, preferably, supplied to the cracking chamber through shaft 12 which for this purpose is shown as a hollow shaft open at its inner end 21 so as to discharge into the cracking chamber. The shaft 12 may be connected with any suitable supply conduit 22 which is longitudinally alined with the outer end of the shaft and connected therewith through a suitable stuffing box 23. Regulating means shown as a valve 24 is provided in the conduit 22 for adjusting the supply of the mineral oils to be treated to the cracking chamber. The mineral oils supplied to the cracking chamber will be vaporized therein during their passage through the portion of the cracking chamber within the furnace 1, and when the vapors reach the portion of the cracking chamber extending beyond the furnace they are condensed within the cracking chamber thereby producing mineral oil distillates.

The means for cooling the vaporous mineral oils is shown as comprising a pipe 25 having spray nozzles 26 for discharging a cooling fluid, such as water, against the outer surface of the cracking chamber. This cooling of the vaporous mineral oils will cause condensation of the latter and the liquefied gases and the fixed gases remaining after the condensation of the vaporous oils together with other liquids that may be present in the condensing portion of the cracking chamber, will be discharged from the outlet end of the cracking chamber.

The discharging means may comprise a plurality of ports 27 arranged circumferentially around the wall of the cracking chamber, preferably, beyond the end of the attrition tube. These ports communicate through nipples 28 with an annular chamber 29 surrounding the cracking chamber and communicating through a discharge pipe 30 with a suitable storage tank 31. The storage tank 31 is shown as provided with a suitable discharge pipe 32 at its lower end controlled by a valve 33, the cranked hydrocarbons being adapted to be removed through said discharge pipe.

In practice it will be found that at the point within the cracking chamber where

the vaporized hydrocarbons are subjected to cooling means for condensing the gases, in addition to the carbon deposits which will be formed upon the apparatus, tarry substances will also be formed from the hydrocarbons within the cracking chamber. If means are not provided for positively removing this tarry accumulation the apparatus will be clogged by the same and the efficient operation of the apparatus will thus be impeded. In order to provide for the removal of such a tarry accumulation a flushing lubricant is, preferably, introduced into the cracking chamber, this lubricant being arranged to dissolve the tarry accumulation within the cracking chamber and discharge the same through the discharge ports 27.

As a practical example of means for thus flushing the cracking chamber I have shown the tank 31 provided with a return pipe 34 leading from the lower portion of the tank to a suitable pump 35 which will cause a portion of the hydrocarbons from the storage tank to be pumped into suitable cooling apparatus shown as comprising a coil 36 through which the hydrocarbons pass and which is arranged to be contacted by a suitable cooling medium shown as a body of water received within a tank 37 surrounding the coil. From the coil 36 the oils, which have thus been reduced to the temperature below that of the condensed hydrocarbons within the cracking chamber, are led through a pipe 38 to suitable means connected with the cracking chamber for introducing said oils into the cracking chamber, preferably, at the end of the portion of said chamber in which the hydrocarbons are vaporized and at the beginning of the condensing portion of the cracking chamber.

As an instance of this arrangement a pipe 39 may project beyond the discharge end of the cracking chamber, this pipe being, preferably, journaled in a bearing bracket 40 and connecting with the pipe 38 through a suitable stuffing box 41. The pipe 39 is shown as closed to the end of the cracking chamber and has communicating branch pipes 42 extending radially beyond the cracking chamber and then longitudinally of said chamber, as shown at 43, so as to discharge into the cracking chamber at the ports 44 arranged at the beginning of the condensing end of the cracking chamber. By this arrangement it will be seen that hydrocarbons at a temperature lower than the distillates formed within the cracking chamber will be injected into the cracking chamber at the start of the condensation of the vaporous hydrocarbons therein, these hydrocarbons of reduced temperature being discharged with the distillates through the discharge ports 27 and acting as a flushing medium for dissolving and carrying

from the cracking chamber any tarry residue which may accumulate therein.

It will be seen that the construction, as thus described, provides a cracking chamber one end of which forms a vaporization chamber, and the opposite ends of which forms a condensing chamber, means being provided for supplying the hydrocarbons to be cracked at the vaporizing end of the chamber and for discharging the hydrocarbon distillates from the opposite end of the chamber.

Furthermore, it will be observed that the improved construction provides an attrition tube within the cracking chamber which may be rotated either in the same or in opposite direction to the direction of revolution of the cracking chamber, this attrition tube being arranged to rub against the wall of the cracking chamber through only a small portion of the circumference of the cracking chamber, but this point of rubbing contact between the attrition tube and the cracking chamber constantly changing throughout the entire circumferences of the tube and chamber so as to positively remove carbon accumulations from all portions of the walls of the tube and chamber.

It will be understood that the driving means for the attrition tube and the cracking chamber may be so regulated as to respectively actuate the tube and chamber at any desired variable speeds for producing any desired relative speed between the contacting surfaces of the tube and chamber. It will be also observed that the improved apparatus provides means for returning a portion of the distillates recovered from the cracking chamber to the latter at a reduced temperature so as to provide a flushing medium for continuously carrying from the cracking chamber the carbon removed from the walls of the apparatus as well as any tarry accumulations formed in the cracking chamber during the vaporization and subsequent condensation of the hydrocarbons.

Various changes may be made without departing from the spirit of the invention as claimed.

What is claimed is:

1. An apparatus for treating mineral oils comprising a rotatable cracking chamber, and an attrition tube rotatable within said chamber, said cracking chamber and attrition tube being rotatable in the same direction and in opposite directions.

2. An apparatus for treating mineral oils comprising a rotatable cracking chamber, and an attrition tube rotatably mounted within said cracking chamber, said cracking chamber and attrition tube being rotatable at different relative speeds.

3. An apparatus for treating mineral oils

comprising a rotatable cracking chamber, 65 and an attrition tube rotatably mounted within said cracking chamber, said cracking chamber and attrition tube being rotatable at different relative speeds in the same direction and in opposite directions. 70

4. An apparatus for treating mineral oils comprising a cracking chamber and an attrition tube within said cracking chamber, and means for rotating said cracking chamber and said attrition tube, said tube 75 and chamber being arranged for rubbing contact throughout a portion of the circumferences of said tube and chamber.

5. An apparatus for treating mineral oils comprising a cracking chamber and an attrition tube within said cracking chamber, 80 and means for rotating said cracking chamber and said attrition tube, said tube and chamber being arranged for rubbing contact throughout a portion of the circumferences 85 of said tube and chamber, the remaining portions of the circumferences of said tube and chamber being spaced apart, said space tapering in width longitudinally of said tube and chamber. 90

6. An apparatus for treating mineral oils comprising a cracking chamber, an attrition tube within said cracking chamber, means for independently rotating said cracking chamber and said attrition tube, said chamber and tube arranged for rubbing contact 95 throughout a portion of the circumferences of said tube and chamber, and means for injecting a flushing medium into said cracking chamber. 100

7. An apparatus for treating mineral oils comprising a cracking chamber having a vaporizing end and a condensing end, an attrition tube within said cracking chamber, means for independently rotating said cracking chamber and said attrition tube, said tube and chamber being arranged for rubbing contact throughout a portion of the circumferences of said tube and chamber; and means for cooling a portion of the discharge from said cracking chamber and returning the same to said cracking chamber between the vaporizing and the condensing ends thereof for flushing said cracking chamber. 110 115

8. An apparatus for treating mineral oils comprising a rotatable cylindrical cracking chamber, an attrition tube within said cracking chamber formed as an oblique cone, said cone having one side thereof perpendicular to its base and resting against the cracking chamber, and a shaft having a universal joint connection with the base of said cone for rotating the attrition tube relative to said cracking chamber. 120 125

In testimony whereof I have signed my name to this specification.

ERNEST VICTOR STONE.
